PLAYGROUND CLIMBING TOWER

Robert S. Wormser, Mexico, Pa., assignor to The Mexico Forge, Inc., Mexico, Pa., a corporation of Pennsylvania

Application September 30, 1958, Serial No. 52,823

Term of patent 14 years

(Cl. D34—5)

Fig. 1 is a front perspective view of a playground climbing tower showing my new design; and

Fig. 2 is a section along line 2—2 of Fig. 1.

I claim:

The ornamental design for a playground climbing tower, substantially as shown.
